PLIER WRENCH

Ted Neff, 20975 Shamrock Ave., San Bernardino, Calif.

Filed Mar. 28, 1963, Ser. No. 74,182

Term of patent 14 years

(Cl. D54—13)

FIG. 1 is a side elevational view of a plier wrench, showing my new design;

FIG. 2 is an elevational view of one edge view thereof;
FIG. 3 is an elevational view of the other edge thereof;
FIG. 4 is a cross-sectional view thereof taken on line 4—4 of FIG. 1; and

FIG. 5 is a reduced fragmentary perspective view thereof.

The undisclosed side is identical to the side shown.

I claim:

The ornamental design for a plier wrench, as shown and described.
